UNITED STATES PATENT OFFICE.

PAUL GANGLER, OF ESSLINGEN, GERMANY, ASSIGNOR TO THE FIRM FR. HESSER MASCHINENFABRIK-AKTIENGESELLSCHAFT, OF STUTTGART-CANNSTATT, GERMANY.

METHOD AND MACHINE FOR MAKING PAPER TUBES.

Application filed October 31, 1922. Serial No. 598,187.

To all whom it may concern:

Be it known that I, PAUL GANGLER, a citizen of the Republic of Wurttemberg, residing at 53 Panoramastrasse, Esslingen, Germany, have invented certain new and useful Improvements in Methods and Machines for Making Paper Tubes, of which the following is a specification.

My invention relates to a machine for 10 making tubes or shells from paper or other suitable material, which are closed at one end, such tubes being used for packing gun powder or the like. It is an object of my invention to provide a simple, efficient, and 15 reliable machine for the purpose specified. The tubes are made in such manner that they will retain their shape under all circumstances.

In the drawings affixed to this specification and forming part thereof a machine embodying my invention is illustrated diagrammatically by way of example. In the drawings—

Fig. 1 is a side elevation of part of the 25 machine,

Fig. 2 a plan of Fig. 1,

Fig. 3 a front-elevation of Fig. 2 viewed from the left,

Fig. 4 an elevation of the severing device,

30 Fig. 5 an elevation and

Fig. 6 a plan of the device for closing the bottom of the tube,

Fig. 7 the wrapping device on a larger scale in sectional side-elevation,

35 Fig. 8 a cross-section along line VII-VII of Fig. 7,

Fig. 9 a similar cross-section with the parts in a different position, and

40 Fig. 10 a side-elevation of the automatic stopping mechanism, viewed from the right-hand side in Fig. 2.

Referring first to Fig. 1 a pulley 3 is loosely mounted on a shaft C with which it may be connected by a clutch 16. The clutch 45 is operated by a lever 17, which is fulcrumed at 19 on a bracket 15' of a casting 15 secured to the foundation plate of the machine. A rod 21 guided in sleeves 45' and 45 is provided with an abutment 47 and a coiled 50 spring 29 which tends to throw out the clutch and to stop the machine.

Normally rod 21 is locked by a mechanism comprising an exchangeable ratchet

wheel 56 on a shaft 57 and pawls 92 and 94 adapted to engage the teeth of the wheel 56.

The purpose of this mechanism is to stop the machine when a predetermined number of tubes has been made. The number of teeth of the ratchet wheel is equal to the 60 number of tubes which shall be produced at one setting, say 25. The tubes are formed on a mandrel 20. A block 100 at the end of a lever 110 mounted on a shaft 101 compresses the end of the tube after it has been 65 closed and returns to its initial position (shown in Fig. 2) when a tube is stripped from the mandrel. Every movement of the lever 110 feeds the ratchet wheel 56 forward 70 one tooth by means of a lever 91 and its pawl 92 until the desired number of tubes has been produced. A dog 111 provided on the ratchet wheel releases the rod 21 after the completion of a set of tubes and allows 75 a spring 29 to throw out the clutch 16. This 80 automatic stopping device forms no part of the present invention and is therefore not described in detail.

The driving shaft C causes rotation of the main shaft A of the machine through the 80 medium of a pinion 5 which meshes with a spur wheel 4 on the shaft A. Shaft A is supported at one end in the casting 15 on which is formed the bracket 15', and by any suitable means, not shown, at the other. 85

The material from which the tube is to be formed a strip P of paper cardboard or the like is drawn from a supply (not shown) by rollers 1 and 2 (Fig. 1) and fed intermittently on a table T a length equal to the 90 size of the sheet B which is required for making one tube. The sheet B is held down on the table T by means well known in the art and therefore not shown. The device for intermittently feeding the material P 95 is also known in the art and not shown either. On the right of the rollers 1, 2 in Figs. 1 and 2 is disposed a printing and numbering apparatus of any known and therefore not shown construction, by means of which the web of paper is provided with any desired printed matter and also consecutive numbering after each forward motion. This impression is placed in such a position 100 that it is situated at the right-hand edge of the subsequently cut off leaf of paper B, 105

as indicated at S in Fig. 2. In this manner, the possibility is given to provide the tubes with any desired printing at the outside.

- The severing device is so arranged in relation to the table T that the web of paper is cut through obliquely, so that the sheet of paper B cut off has the rhombic shape shown in Fig. 2, and possesses a projecting corner at the front as well as at the back.
- 10 This manner of cutting off the individual leaves from the continuous web is extremely important, inasmuch as the corner at the front of the leaf facilitates the introduction of the leaf B into the wrapping or folding device, and because the corner at the rear which is utilized to form the bottom of the tube, effectively prevents the unwrapping of the tube or shell.

The paper serving device, Figs. 1, 2 and 20 4, consists in the present case of a shear-like construction, a movable knife 6 pivoted on the bolt 8 cooperating with a stationary cutting edge of the table T and being swung up and down by the aid of a lever 7, link 10, the slide 11 upon the rod 9, the bell-crank 12 and friction roller 13 resting against the cam 14 fixed upon the driving shaft A.

- A mandrel 20 serves for wrapping or 30 folding the leaf B cut off into the tube or shell. One end of this mandrel is disposed in a suitable ball-bearing 35, Fig. 7. The mandrel is recessed to a certain length and width, Figs. 7-9, for the reception of a 35 gripper adapted to engage the leading point of the cut-off sheet B. In the present case, this device consists of a finger 22, which by a spindle 109 and bearings 23, 24 with eyes is hinged within the recess of the mandrel.
- 40 Upon the spindle 109 is also fulcrumed a double-armed swing lever 25, one arm of which is acted upon by a spring 26 fixed upon the mandrel, and the other arm of which is controlled by a lever 27 fulcrumed at 45 28' which by means of a link 28 is oscillated in any well-known manner, for instance, by a lever 151 pivotally supported at 150 to which the link 28 is pivoted at 152. A pull-back spring 153 connected to the 50 lever 27 tends to hold the lever 151 with its roller 154 against the face 155 of a cam 156 secured on the main shaft A. In its extreme outer position represented in Fig. 8, the lever 27 sets the lever 25 free, so that its arm which is under the action of the 55 spring 26, is forced against the gripper-plate 22, which in its turn is pressed against the mandrel, whereby the leading point of the sheet B is gripped and held by it. In its inner position shown in Fig. 9, the lever 27 turns the lever 25 against the resistance of the spring 26 into such a position, that the spring 26 is raised and releases the 60 gripper 22, which in its turn releases the corner of the sheet of paper.

The rotation of the mandrel is effected by the following device: On the bolt 42' is fulcrumed a bellcrank lever 42, one arm of which is furnished with a bowl 43, which runs in a circular groove 44 with an inclined plane provided in a barrel 108 keyed upon the driving shaft A, whereby a continuous oscillating motion is imparted to the lever 42. The other arm of the bellcrank 42 is formed as a toothed segment 142, which meshes with a pinion 41 revolving upon a bolt 40. With this pinion cooperates a pawl 38 pivoted at 39 upon a spur wheel 37 also revolving upon the bolt 40 in such a manner, that when the pinion 41 is rotated clockwise by the segment 142, the spur wheel 37 is also rotated clockwise by the pawl 38 and through the spur wheel 36 also rotates the wrapping mandrel 20. If on the other hand the pinion 41 is turned in the opposite direction by the segment 142, the pawl 38 slides over the teeth of the pinion 41 and remains inoperative, so that the mandrel 20 remains stationary. A braking action is exerted upon the mandrel 20 by a brake disc 30 fixed upon it, Figs. 7-9, upon which can ride a brake shoe 31 fixed upon the lever 27 by means of a spring 32.

The formation of the bottom of the tube is effected by the folding slides 60, 65, 76 and 81. The side slides 76, 81 are fixed upon levers 77, 80, pivoted at 79 and kept in contact with a cam 83 upon a short shaft 84 by means of bowls 78, 82. The motion of the cam 83 is effected by means of a link 85 from a lever 86 fulcrumed at 87, which by a crank 88 with bowl 89 is operated from a cam 90.

The lower folding slide 60 is fixed upon a sleeve 61, which is adapted to slide upon a guide-post 69 and is moved up and down by a link 62 and a lever 63 in a well-known manner from a suitable driving device not shown.

The folding slide 65 is pivoted upon the bolt 67 of a sliding carriage 72, which is vertically reciprocated upon the guide-post 69 by means of a link 73 and driving lever 74. The folding slide 65 is held with the lever 66 against a roller 71 upon a bolt 70 fixed upon the post 69 by a spring 68, the lever 66 being so arranged or shaped, that the folder 65 performs a swinging movement towards the mandrel during its downward motion.

The ejecting device for the finished paper tubes consists of a rod 50 slidably disposed within the mandrel, which is moved to and fro by means of a link 52 hinged at the head 51 of the rod, double-armed lever 53, connecting link 54 and double-armed lever 58 with bowl 59 bearing against a cam upon the first-motion shaft A.

In order to more effectively prevent a bursting open of the tube by forcing its bot-

tom inwards, the head of the ejecting rod 50 is made concave at 210', and with this cavity cooperates a convex punch 100, which is fixed upon the shaft 101 rotatably mounted in the standard 102 by an arm 110. The shaft 101 has a rocking motion imparted to it by a crank 103, link 104 and bellcrank lever 105 with bowl 106 operated by a cam upon the shaft A.

- 10 When the buffer 100 is moved from the position shown on Fig. 2 into its operative position to compress the end of a tube on the mandrel 20 the ratchet wheel 56 is rotated one tooth by the pawl 92 on the lever 91. This is repeated each time a tube is formed until the ratchet wheel 56 has been rotated a certain number of teeth, whereupon the rod 21 is released, throwing out the clutch 16 and stopping the machine.
- 15 The tube is formed in the following manner: When the paper is fed forward, the leading corner passes between the open gripper 22 and the mandrel, Fig. 9, whereupon the gripper 22 is closed and tightly grips the leading corner between itself and the recess of the mandrel. After a leaf B has been cut off the web of paper, the mandrel has the number of revolutions required to form the tubular shell imparted to it by the 20 operating device described, whereupon the mandrel is subjected to a braking action by the braking device described and then the bottom is formed first by the upper slide 65, then the lateral slides 76, 81 and finally 25 by the lower slide 60. After the slides have receded, the punch 100 advances and forces the folded bottom into the concave recess 210'. During the braking of the wrapping mandrel, the gripper 22 has released the 30 corner of the sheet B which it clamped up to them, so that the shell can be stripped off the mandrel by the rod 50 and ejected into the chute 200.

After the set of finished tubes has been removed from the machine, the lever 17 is operated by hand to throw in the clutch 16, and locked in its position by the rod 21, whereupon the next set is started.

It will be understood that I do not limit myself to the exact details of the machine shown by way of example, but that these details may be modified in various ways without departing from the spirit of the invention or sacrificing any of its advantages.

55 I claim:

1. Machine for making paper tubes comprising a mandrel, means for rotating said mandrel, means for feeding tube forming material towards said mandrel, means for cutting rhombic sheets from the material, means for operating said cutting means, a gripper hinged in a recess of said mandrel and adapted to engage the leading point of the rhombic sheet and means for operating 60 said gripper.

2. Machine for making paper tubes comprising a mandrel, means for rotating said mandrel, means for feeding tube forming material towards said mandrel, means for cutting rhombic sheets from said material, 70 a gripper hinged in a recess of said mandrel and adapted to engage the leading point of the rhombic sheet, a double armed lever fulcrumed on the hinge pin of said gripper, a spring adapted to act on one arm of said 75 double armed lever and to close said gripper, a lever adapted to depress the other arm of said double armed lever and means for oscillating said depressing lever.

3. Machine for making paper tubes comprising a mandrel, means for rotating said mandrel, means for feeding tube forming material towards said mandrel, means for cutting rhombic sheets from said material, 80 a gripper hinged in a recess of said mandrel, means for operating said gripper, mechanism for folding the end of the paper tube projecting beyond said mandrel comprising an upper folder, two lateral folders and a lower folder and means for operating 85 said folders in succession.

4. Machine for wrapping paper tubes comprising a shaft, a mandrel adapted to rotate about said shaft, a toothed segment adapted to rotate said mandrel, means for 90 intermittently rocking said toothed segment, means for feeding tube forming material towards said mandrel and means for cutting the material into sheets of predetermined size.

5. Machine for wrapping paper tubes comprising a shaft, a mandrel adapted to rotate about said shaft, a toothed segment adapted to rotate said mandrel, a cam operatively connected with said toothed segment 105 and adapted to impart intermittent rotation thereto, means for rotating said cam, means for feeding tube forming material towards said mandrel and means for cutting the material into sheets of predetermined size.

6. Machine for making paper tubes comprising a mandrel, means for rotating said mandrel, means for feeding tube forming material towards said mandrel, means for cutting rhombic sheets from the material, means for operating said cutting means, a brake drum on said mandrel, a brake block adapted to cooperate with said mandrel and automatic means for applying said brake 115 block to said drum.

7. Machine for making paper tubes comprising a mandrel, means for rotating said mandrel, means for feeding tube forming material towards said mandrel, means for cutting rhombic sheets from said material, a gripper hinged in a recess of said mandrel and adapted to engage the leading point of the rhombic sheet, a brake drum on said mandrel, a double armed lever fulcrumed on the 125 130

hinge pin of said gripper, a spring adapted to act on one arm of said double armed lever and to close said gripper, a lever adapted to depress the other arm of said 5 double armed lever, a brake block adapted to be applied to said brake drum and automatic means for operating said gripper and applying said brake block.

8. Machine for making paper tubes comprising a mandrel, means for rotating said mandrel, means for feeding tube forming material towards said mandrel, means for cutting rhombic sheets from said material, a gripper hinged in a recess of said mandrel

and adapted to engage the leading point of 15 the rhombic sheet, a brake drum on said mandrel, a double armed lever fulcrumed on the hinge pin of said gripper, a spring adapted to act on one arm of said double armed lever and to close said gripper, a 20 lever adapted to depress the other arm of said double armed lever, a brake block adapted to be applied to said brake drum operatively and resiliently connected with said depressing lever and means for oscillating said depressing lever. 25

In testimony whereof I affix my signature.
PAUL GANGLER.
